FLUID PUMP

John G. Lee, Farmington, Conn., assignor to United Aircraft Corporation, East Hartford, Conn., a corporation of Delaware

Filed Dec. 6, 1962, Ser. No. 242,693
11 Claims. (Cl. 103—1)

This invention relates to energy conversion devices and more particularly to pumping devices having very low friction, especially when used to pump slurries, gritty substances, and other non-lubricating fluids.

It is an object of this invention to provide a pumping device which operates on a principle similar to vane pumps but in which the normal mechanical vanes are replaced by fluid vanes.

It is a further object of this invention to provide fluid-type vanes which divide the work chamber of the pump into two or more compartments with the fluid vanes forming a barrier between adjacent compartments which contain the pumped fluid at different pressure levels.

These and other objects of this invention will become readily apparent from the following detailed description of the drawing in which:

FIG. 1 is a cross section of one form of pump utilizing this invention and having a lobed rotor.

FIG. 2 is a cross section of another type of pump utilizing the same principle but having an eccentrically mounted circular rotor.

FIG. 3 is a cross section of another type of pump utilizing the same principle but incorporating a circular slotted rotor.

FIG. 4 is a partial sectional view illustrating a canting passage for the auxiliary injection for pumps of the type shown in FIGS. 1 and 2.

Referring to FIG. 1, a pump casing 10 forms a main working chamber 12 in which is mounted a concentric rotor 14 having several lobes 16 and 18. The rotor 14 is mounted on a shaft 20 by means of a key 22. The shaft 20 includes a plurality of openings or slots 24 which communicate with corresponding passages 26 and 28 in the lobes 16 and 18, respectively. Fluid is fed into the shaft 20 for discharge, for example, through the passage 26 and out through the peripheral opening 30 at the outer end of the lobe 16. The fluid flow from the opening 30 is intended to form a fluid seal between adjacent compartments formed by the lobes on the rotor.

The pump casing includes inlet passages Y₁, Y₂, and Y₃, and likewise output passages X₁, X₂, and X₃ are intended to conduct the compressed or pressurized fluid from the pump. The auxiliary passages Z₁, Z₂, and Z₃ provide a wall of fluid schematically illustrated as, for example, at 40 which divides the inner lobe cavity into a low pressure region 42 and a high pressure region 44.

It will be apparent that as the rotor 14 turns in a clockwise direction and with the fluid wall 40 substantially fixed relative to the casing, the chamber 44 will diminish in size while the chamber or compartment 42 will increase in size so that the fluid in chamber 44 will be compressed and expelled from the passage X₃ while the enlarging volume of compartment 42 will draw in fluid through the inlet passage Y₃. The fluid wall 40 will assume a curved or bend configuration with the bend moving away from the high pressure region.

There may be some fluid leakage as each of the lobes pass a group of ports but overall fairly high pumping efficiencies can be achieved. As a result of the arrangement just described and the principle of operation utilized, extremely low friction is obtained and substantially no wear is encountered since there is no rubbing of any mechanical parts, except at the end of the rotor.

FIG. 2 shows a modified pump arrangement utilizing

2

substantially the same principle as that employed in FIG.

1. Thus, it will be seen that the casing 50 includes inlet ports C₁, C₂, and C₃ and outlet ports B₁, B₂, and B₃. Auxiliary passages A₁, A₂, and A₃ conduct the fluid for forming the fluid vanes or fluid walls 52. The fluid walls intercept a substantially solid rotor 54 whose center is mounted on a shaft 56 which in turn is connected to a crank 58. A drive shaft 60 drives the rotor assembly such that the outer periphery 62 of the rotor rolls along the internal periphery 64 of the pump casing. No special sealing is necessary between the rotor and the pump casing wall since it is in substantially continuous engagement therewith. The rotor may, in fact, be made of some flexible material such as rubber, and be held against the wall tightly by slight mechanical distortion. In operation the pump otherwise operates in a substantially identical manner to the FIG. 1 arrangement.

FIG. 3 illustrates another form of pump arrangement having a main casing 70 and inlet and outlet ports 72 and 74, respectively. In this arrangement the drive shaft 78 is hollow and the rotor 80 is provided with slots so that the auxiliary fluid for forming the fluid vanes can be emitted through the passages 82 of the rotor. In this instance the auxiliary fluid flows from the rotor and intercepts the casing wall. No other special sealing means is required with this arrangement. It will be noted, however, that the pumped fluid is trapped in a series of chambers, 93, 94, 95, etc., each separated from the next by a fluid wall, and that the pressure delivered by the pump is several times greater than the pressure across any single fluid wall.

Some of the compressed flow from outlet 74 may be bled off and conducted into shaft 78 to provide the auxiliary flow for ports 82.

Inasmuch as the fluid wall tends to curve or bend away from the high pressure region, the auxiliary flow may be injected into the working chamber by a canted discharge passage 90 as shown in FIG. 4. In this way, the stream of auxiliary flow is directed against the force of the high pressure region so that even though the fluid wall 92 will bend toward the low pressure region it will not be so easily deflected toward the latter region.

It will be obvious to one skilled in the art that the ends of the rotors may be sealed by a fluid discharge from the rotor axially against the casing, or conversely, by a discharge from the casing axially against the end of the rotor.

Although several embodiments of this invention have been described, it will be apparent that other variations and changes may be made in arrangement and construction of the various elements without departing from the scope of this novel concept.

I claim:

1. A fluid pump comprising a stationary casing means, a member being rotatable relative to said casing means and having an outer surface, said casing means and said member forming at least one working chamber, inlet and outlet passages in said casing means for admitting and exhausting the fluid to be pumped, and fluid injection means for forming a fluid wall and dividing said chamber into sections having different pressure levels during operation including auxiliary passage means in the wall of said casing for injecting relatively high energy fluid which flows between said casing means and intercepts the outer surface of said member.

2. A fluid pump according to claim 1 wherein said member includes an element in close operable proximity to said casing means and substantially in sealing relation therewith.

3. A fluid pump according to claim 2 wherein said auxiliary passage means directs fluid at an angle toward the section having the higher pressure.

4. A fluid pump comprising a stationary casing means having an inner surface, a member being rotatable rela-

tive to said casing means, said inner surface of said casing means and said member forming at least one working chamber, inlet and outlet passages in said casing means for admitting and exhausting the fluid to be pumped, and injection means for forming a fluid wall for dividing said working chamber into sections having different pressure levels during operation including auxiliary passage means in said casing means for injecting relatively high energy fluid which flows from said casing means and intercepts said member.

5. A fluid pump according to claim 4 including a second auxiliary source of fluid flowing between said casing and said member to form a fluid seal therebetween.

6. A fluid pump according to claim 5 wherein said member includes a plurality of lobes defining working chambers therebetween.

7. A fluid pump according to claim 4 wherein said member comprises a roller engaging the internal periphery of said casing and being of smaller dimension than said working chamber and eccentric with respect thereto.

8. A fluid pump comprising a stationary casing means having an inner surface, a member being rotatable relative to said casing means, the inner surface of said casing means and said member forming at least one working chamber, inlet and outlet passages in said casing means for admitting and exhausting the fluid to be pumped, and fluid injection means for forming a fluid wall for dividing

4
said chamber into adjacent sections having different pressure levels during operation, and passage means in said member for injecting relatively high energy fluid which flows from said member to intercept said casing means and said inlet and outlet passages.

5. A fluid pump according to claim 4 wherein said member is eccentric with respect to said casing means and has a rolling contact therewith.

10. A fluid pump according to claim 8 including additional injecting means in said casing and located between said inlet and outlet passages for issuing a stream of fluid intercepting said member.

11. A fluid pump according to claim 10 wherein said member is concentric with respect to said casing.
